UNITED STATES PATENT OFFICE

JOSEPH F. BABITT, OF WELLINGTON, OHIO

SAFETY APPLIANCE FOR LADDERS

Application filed February 20, 1931. Serial No. 517,216.

This invention relates to safety appliances for ladders and the object of the invention is to prevent the ladders from slipping when in use. The invention comprises two interchangeable units which can be quickly mounted on the foot of the ladder, the metal prong unit being intended for ground use, and the rubber unit for use on floors or the like.

10 In the accompanying drawings:

Fig. 1 is a perspective view of the non-slipping ladder device for floors, etc., fitted to the ladder; Fig. 2 is similar to Fig. 1 except that the floor device is removed and the 15 ground gripper exposed; Fig. 3 is a side elevation of the floor device; Fig. 4 is a front elevation of the same; Fig. 5 is a rear elevation of the same; Fig. 6 is a section taken on lines 6—6 of Fig. 5; Fig. 7 is a perspective 20 view of the floor device structure before the rubber or like material is applied; Fig. 8 is a detail in front elevation of the ground gripper, showing the prongs; Fig. 9 is a detail of the side elevation of the ground gripper.

25 Referring to the drawings:

10 indicates the ladder, to each leg of which is attached a bracket member 12 by means of long bolts 11 through apertures 11a in the said bracket member 12, which is flanged, 30 forming sides 13 and 14 each of which has ears 15 and 16 respectively, near its middle portion, with apertures 17 and 18 respectively through which the pivot bolt 19 extends. The bolt 19 engages in the apertures 20 and 35 21 in the side flanges 22 and 23 of a ground gripper member 24 which is mounted between the ears 15 and 16 of the bracket member 12 and within the spacer 25, the bolt being held in position by lock washer 26 and 40 nut 27.

The prongs 28, 29 and 30 of the ground gripper are cut on an angle as shown in Fig. 9 to form a sharp edge which permits the prongs 28, 29 and 30 to sink slightly into the 45 ground, thus preventing the ladder from slipping, and when set up the upper end of the gripper 24 stops against the back of the plate 12 and holds the gripper in upright position.

50 Slightly above the prong 29 is an aper-

ture 32 which is used when the floor device 33 is mounted upon the ground gripper 24. The floor device 33 consists of a flat strip of metal bent over at 34 and 35, towards the middle, the ends being bent to form upstanding ears 55 or lugs 36 and 37 respectively, the tops of which are bent outward. Each flanged surface 38 and 39 has a plurality of countersunk holes 40 which are filled with the melted rubber 41 or like material when the metal 60 strip is laid in a mold and embedded in the said material 41. The base of the floor device has a plurality of corrugations 42, which adhere to the surface of any type of floor, thus preventing skidding or sliding. 65 This floor device is attached with the prongs 28, 29 and 30 mounted between the ears 36 and 37 and is secured by a bolt 43 projecting through the apertures 44 and 45 in the ears 36 and 37 and the aperture 32 in the ground 70 gripper 24, and held by nut 46.

The floor device may be applied when the ladder is used on floors, or removed when used on the ground.

I claim:

A floor piece for a safety device for ladders comprising a metal plate folded upon itself at each end, the plate having holes extending therethrough and the adjacent ends of the plate having lugs struck up therefrom for attachment to the device, and a rubber block moulded upon and around the plate and extending through said holes.

In testimony whereof, I do affix my signature.

JOSEPH F. BABITT.
